UNITED STATES PATENT OFFICE.

JAMES E. FROMAN, OF EVANSVILLE, INDIANA.

CRADLE OR CRIB.

1,224,525.

Specification of Letters Patent.

Patented May 1, 1917.

Application filed January 25, 1916. Serial No. 74,205.

To all whom it may concern:

Be it known that I, JAMES E. FROMAN, a citizen of the United States, residing at Evansville, in the county of Vanderburgh, 5 State of Indiana, have invented certain new and useful Improvements in Cradles or Cribs; and I do hereby declare the following to be a full, clear, and exact description of the invention, such as will enable others 10 skilled in the art to which it appertains to make and use the same.

This invention relates to improvements in cradles and cribs for infants.

One object of the invention is to improve 15 the construction of devices of this character so that they may be easily and conveniently moved from place to place.

Another object is to provide a device of 20 this character which will be comfortable to the infant and by means of which a general bouncing motion can be produced in a simple and easy manner which is especially desirable at night.

Other objects and advantages will be apparent from the following description when taken in connection with the accompanying drawing.

In the drawing:

Figure 1 is a side elevation of a crib made 30 in accordance with my invention;

Fig. 2 is a rear elevation;

Fig. 3 is a top plan view;

Fig. 4 is a transverse section on the line 4-4 of Fig. 1.

Fig. 5 is a side elevation of a modified 35 form of the device; and

Fig. 6 is a front elevation of the form shown in Fig. 5.

Referring particularly to the accompanying drawing, 40 10 represents a horizontally disposed and longitudinally extending member, the forward end of which is turned upwardly as indicated at 11 where it is connected to a vertically disposed crescent-

45 shaped frame member 12. The other end of the member 10 extends up a greater distance than the front end, as shown at 13, and is provided with a cross member 14 serving as a handle. A pair of transverse axles 15 are

50 secured respectively to the front and rear

end portions of the member 10 and carry on their ends the wheels 16. A second shorter crescent-shaped member 17 is disposed above the first crescent-shaped member and has its ends secured to the first member as at 18. 55 The intermediate portions of the members 12 and 17 are spaced apart by the members 19. The upper ends of the member 12 are turned downwardly and inwardly where they are formed with a pair of openings for 60 the reception of the upper ends of the coil springs 20. The lower ends of these springs are connected to a horizontally disposed, and approximately rectangular band 21, within which the basket 22 is inserted, the upper 65 strip or band 23 of the basket resting on the upper edge of the band 21. While I have shown the basket in its proper position, it forms no constructive part of the device as herein presented, but may be included with 70 the device when placed on the market or omitted, as seen fit.

Referring particularly to Figs. 5 and 6 there is shown a modified form of the device in which there are no front wheels, the front 75 of the frame being supported by the arcuate member 24 secured to the forward end of the member 10' and having the ends of the said member so arranged as to form feet. In this form, the device is moved 80 by tilting rearwardly to raise the front portion and thus permit of the entire device being supported on the wheels 25. The device can then be pushed to any desired position.

Referring again to Figs. 1, 2, 3, and 4 in 85 the rear, there is mounted a bracket 26, in which is disposed a transversely extending flexible strip 27, the ends being arranged for engagement with the treads of the rear wheels. An angle lever 28 is pivotally 90 mounted in the bracket and is adapted to be moved by the foot to bow the intermediate portion of the strip and thus cause the ends thereof to move downwardly into frictional engagement with the wheels. 95

What is claimed is:

An infant's crib comprising a wheel supported frame including properly connected arcuate members, the arms of one of the members extending vertically in spaced re- 100

lation, resilient suspending elements carried by the said arms, a ring connected to and suspended from and between the resilient elements, and a basket detachably received
5 within the ring and formed with a shoulder for supporting engagement with said ring.

In testimony whereof, I affix my signature, in the presence of two witnesses.

JAMES E. FROMAN.
